COIN BANK

Russell L. Rust, San Marino, Calif.

Application March 23, 1949, Serial No. 1,578

Term of patent 7 years

(Cl. D34—11)

To all whom it may concern:

Be it known that I, Russell L. Rust, a citizen of the United States, residing at San Marino, in the county of Los Angeles and State of California, have invented a new, original, and ornamental Design for Coin Bank, of which the following is a specification, reference being had to the accompanying drawing, forming a part thereof.

I claim:

The ornamental design for a coin bank, substantially as shown.

RUSSELL L. RUST.
